UNITED STATES PATENT OFFICE.

FREDERICK W. MEIER, OF UPPER SANDUSKY, OHIO.

WATER-TRAP.

No. 901,922.

Specification of Letters Patent.

Patented Oct. 20, 1908.

Application filed June 3, 1908. Serial No. 436,401.

To all whom it may concern:

Be it known that I, FREDERICK W. MEIER, a citizen of the United States, residing at Upper Sandusky, in the county of Wyandot and State of Ohio, have invented certain new and useful Improvements in Water-Traps, of which the following is a specification, reference being had therein to the accompanying drawing.

- 10 This invention relates to improvements in sewer traps, and the main object of my invention, is the production of a trap, adapted to be used especially in cellar drains, and which are so constructed as to be readily and 15 quickly installed, and which will allow all water to flow into the sewer or drain, but will prevent the escape of sewer gas or the backing-up water through the trap, from rising waters, into the cellar.
- 20 This improved trap, comprising primarily a casing, which is adapted to fit horizontally into the upper end of the drain pipe, and is provided with a screen at its mouth to prevent large obstacles from entering the casing, and is further provided with a truncated-conical member having an open lower end, over which swingingly, tiltingly and 25 slidably fits a similarly shaped closed bottom member, which when the water enters the casing will allow the same to flow into the drain pipe, but which when the water begins to back will rise, closing the lower open end of the truncated conical member, so that no egress of water or gas is allowed beyond this 30 point. In order to assist in the easy operation of the trap, I mount the same upon a roller, which holds the trap properly centered and provides an anti-frictional bearing for the trap.
- 40 To more clearly illustrate my invention, attention is invited to the accompanying drawings, in which:—

Figure 1 is a longitudinal sectional view through my trap and the upper end of a drain pipe, the trap being in the position it assumes when allowing water to pass into the drain. Fig. 2 is a similar view with the parts in the position they assume when preventing the escape of water and gases.

50 Fig. 3 is a cross section on line $x-x$, Fig. 1. Fig. 4 is a cross section on line $y-y$, Fig. 1, and Fig. 5 is a detail view of the trapping member and its guiding means.

55 Referring to the drawings:—The numeral 1 designates a horizontal inlet end of a drain

or sewer pipe, in which is adapted to fit the horizontal outer casing 2, of my invention, the flange 3, resting upon the upper end of the pipe 1 and holding the casing in place therein. This casing 2, has mounted therein 60 the short straight sleeve or pipe 4, which is secured within the casing at its top by means of the device 5, while at its lower edge, I secure it to the casing as at 6. Carried by this pipe 4 and extending into the casing 2, is the 65 inverted truncated spout or member 7, whose lower end 8, is open and is adapted to direct the flow into the drain pipe.

Slidably, swingingly and tiltingly mounted within the casing 2, and below the lower 70 end of the spout or member 7, is the trap or cup 9, which tapers from the closed bottom 10 to the open discharge end 11, the walls 12, being tapered on the same incline as the walls of the spout, so that when the trap or 75 cup 9, is seated the entire lower end of the spout is closed, as shown in Fig. 2. When the trap is allowing water to flow into the drain it assumes the position shown in Fig. 1, and the water flows in the direction of the 80 arrows.

In order to properly guide the trap or cup 9, in its movement and assist in its opening or closing the spout, I mount upon the inside of the casing 2, the rods or runways 13, for the reception of the roller or 85 roller bearing 14, which is journaled in the outer end of the arm or bracket 15, which is carried by the trap or cup 9. One or more of these may be employed without departing 90 from the spirit of my invention.

By mounting the cup 9 as shown, it normally assumes the closed position, as shown in Fig. 2.

In order to prevent obstacles from entering the casing 2 and the spout 7, I place 95 the screen 16 over the upper end of both.

From the foregoing description taken in connection with the drawings, it is evident that I provide a trap of this character and 100 for this purpose, which when made of a non corrodible metal such as brass, is durable and by reason of its long life inexpensive; while at the same time by reason of its simplicity is very practical and useful.

105 What I claim, as new is:—

1. In a trap, the combination of a horizontal casing adapted to be inserted into the end of a drain or sewer pipe, a tapering spout mounted therein, and a trap or cup 110

slidingly and swingingly mounted in the casing below the spout, whereby the spout is opened or closed thereby.

2. In a trap, the combination of a horizontal casing adapted to be inserted into the end of a drain or sewer pipe, of a tapering spout mounted therein, a trap or cup slidingly and swingingly mounted in the casing to control the exit of the spout, and means 10 for guiding the trap or cup within the casing.

3. In a trap, the combination of a horizontal casing adapted to be inserted into the end of a drain or sewer pipe, of a tapering spout mounted therein, a trap or cup slidingly and swingingly mounted in the casing 15 to control the exit of the spout, and anti-frictional means for guiding the trap or cup within the casing.

4. In a trap, the combination of a horizontal casing adapted to be inserted into the end of a drain or sewer pipe, of a tapering spout mounted in the casing and having a reduced lower end, and a tapered cup slidingly and swingingly mounted in the casing 20

below the spout the walls of which are of the same taper as the spout, whereby as the cup swings toward the spout the entire lower end of the spout is sealed by the cup. 25

5. In a trap, the combination with the horizontal inlet of a drain pipe, of a casing adapted to be inserted horizontally in said pipe, a tapered spout carried by said casing, and a cup swingingly mounted within the casing adapted to normally swing toward and cover the mouth of the spout. 30

6. In a trap, the combination of a horizontal casing, a tapered spout mounted therein, a rod mounted within the casing upon the upper side beyond the inner end of the spout, and a tapered cup swingingly 40 connected to said rod, as and for the purpose set forth.

In testimony whereof I affix my signature in presence of two witnesses.

FREDERICK W. MEIER.
